UNITED STATES PATENT OFFICE.

WILLIAM H. HANKIN, JR., AND CORNELIUS TINNEY, OF BROOKLYN, N. Y.

RE-ENFORCING PLATE FOR SAW-HANDLES.

SPECIFICATION forming part of Letters Patent No. 280,612, dated July 3, 1883.

Application filed April 28, 1883. (No model.)

To all whom it may concern:

Be it known that we, WILLIAM H. HANKIN, Jr., and CORNELIUS TINNEY, both citizens of the United States, residing at Brooklyn, E. D., 5 in the county of Kings and State of New York, have invented new and useful Improvements in Re-enforcing Plates for Saw-Handles, of which the following is a specification.

This invention relates to a re-enforcing plate 10 adapted more especially for handsaws; and it consists in the combination, with a saw-blade and a handle, of a re-enforcing plate provided with a groove adapted for the reception of the blade, as hereinafter more fully set forth. 15 The construction of the plate is hereinafter more fully described.

This invention is illustrated in the accompanying drawings, in which Figure 1 is a side view of part of a saw containing the improvement. Fig. 2 is an inverted plan view of the 20 re-enforcing plate. Fig. 3 is a plan view of said plate. Fig. 4 is a section in the plane xx , Fig. 2. Fig. 5 is a section in the plane yy , Fig. 3.

25 Similar letters indicate corresponding parts.

In the drawings, the letter A designates a part of a saw-blade, and B is the handle, the wings of which have slots or holes through which and through corresponding slots or 30 holes in the saw-blade are passed bolts or screws C, by which means the blade and handle are connected. The tail I of the blade A extends under the bridge H of the handle. A difficulty heretofore experienced has been the 35 liability of the bridge H to break by the strain put upon it in the operation of the saw. To avoid this difficulty we provide a re-enforcing plate, D, which extends along the bridge H. A convenient way of attaching the plate D is 40 by a screw, G, as shown in Fig. 1.

Figs. 2 to 4, both inclusive, show in detail the construction of the re-enforcing plate D. The same consists of a head, K, which can be adapted for the accommodation of the screw 45 G, Fig. 1, or other fastening device for attaching the plate to the handle. From the head

K extend wings or arms e e, connected at or near their outer ends by a bridge, f. This bridge f is so arranged as not to break the space or groove between the wings e e, said 50 space or groove being intended for the accommodation of the tail I of the blade A. As seen from Fig. 1, the blade, handle, and re-enforcing plate, when adjusted and attached in place, are firmly held together, and the whole 55 makes a strong and durable device, which at the same time is light and easy to handle.

Of course we may modify the construction of the plate D by extending the bridge f along the entire upper face of the plate and making 60 said bridge f continuous with the head K; but the construction shown in the drawings furnishes a sufficiently strong device, and as the least amount of metal is used the device is lighter and cheaper. As shown in Fig. 3, the 65 top of the bridge f is flush with the top of the wings of the plate D, so that the top of the device offers an even surface, while the under side of the bridge f lies above the lower surface of the wings e e, so that the space between 70 said wings which is adapted for the insertion of the tail I of the blade A is not broken.

What we claim as new, and desire to secure by Letters Patent, is—

1. The combination, with a saw-blade and a 75 handle, of a re-enforcing plate provided with a groove to receive the tail of the blade and applied to the bridge of the handle, substantially as described.

2. A re-enforcing plate for saw-handles, consisting of a head, K, arms or wings e e, an intermediate groove, and a bridge, f, substantially as described.

In testimony whereof we have hereunto set our hands and seals in the presence of two 85 subscribing witnesses.

WILLIAM H. HANKIN, JR. [L. S.]
CORNELIUS TINNEY. [L. S.]
